IGNITION SYSTEM

Application filed September 10, 1930. Serial No. 480,977.

My invention relates to an ignition system more especially intended for use with what are known as gas-electric internal combustion engines in which each cylinder is usually 5 provided with four spark plugs.

The object of my invention is to provide an ignition system wherein perfect synchronization of the sparks at all spark plugs of each cylinder of the engine to be fired is accomplished; while at the same time a system is provided which eliminates the use of high tension voltage in the distributing mechanism and its conductors and as a result overcomes the high tension voltage leakage heretofore 15 encountered.

Furthermore, as a result of the use of my improved system, sparking at the contacts of the distributing mechanism or brush is also eliminated.

20 The objects and advantages of my invention will be readily comprehended from the following detailed description of the accompanying drawing wherein—

The figure is a schematic illustration of 25 the system as applied to a multi-cylinder engine; the well known means for operating certain of the elements not being shown.

My improved ignition system is especially 30 intended for gas-electric internal combustion engines which are usually provided with a multiple of cylinders, as for example from six to eight or more.

For purposes of exemplification, I have 35 chosen to illustrate an engine having six cylinders which are generally indicated at 10, 10^a, 10^b, 10^c, 10^d, and 10^e; while the head or block of each cylinder is shown provided with four spark plugs which are indicated at 40 11 arranged in the usual conventional manner.

The spark plugs in ignition systems as 45 heretofore employed were grounded; whereas my invention contemplates an ungrounded high tension ignition system using two or more high tension coils at 12.

The primaries 13 of the different coils 40 of all the cylinders are all connected in series through a distributing mechanism indicated at 14, with a primary circuit inter-

rupter mechanism indicated at 15, and a suitable battery indicated at 16.

With this arrangement a complete series circuit is provided when the distributing mechanism brush 17, is on one of the contact points 18 and the interrupter mechanism 15, is in closed position.

The secondary circuit of the high tension coils 12, may consist of two or more coils 19, connected in series with four or more spark 60 plugs 11, of the respective cylinders of the internal combustion engine.

Where two coils are used for each cylinder on a multi-cylinder internal combustion engine with four spark plugs in a cylinder, 65 both ends of the secondary winding 19, of each coil 12 are to be connected in series with the insulated electrode of two of the four spark plugs 11, in that cylinder, either with or without an intensifier in the series and for 70 that reason I have not shown an intensifier.

The distributing mechanism is shown in the nature of an annular member or ring 20, which is provided with a number of contact 75 points 18, in keeping with the number of cylinders, and spaced apart equi-distances as indicated.

Each contact point 18 of the distributing mechanism 14, is connected with the primary 80 of a coil 12.

The other pole of the battery 16, is connected by wire 40 with the primary circuit interrupter mechanism 15, which is connected by wire 41, with the brush 17, of the distributing mechanism.

The line 40, leading from battery 16, to the interrupter mechanism 15, is shown provided with a suitable switch at 42; and I prefer to provide the line 24, with a suitable lamp or bulb as at 43. The bulb 43, is preferably of 90 a capacity equal to the coils 12 on the engine, so that when the current flow is greater than the capacity of the respective coils, the lamp or bulb 43, will light and give indication to the operator of some improper condition; the 95 lamp or bulb 43, controlling the voltage on the circuit.

It will be understood, of course, that the brush or distributor arm 17, is rotated by suitable gears from the shaft (not shown) 100

which is intended to be operated by the engine and which shaft, by suitable means, operates the cam-shaft 44, of the interrupter mechanism 15.

5 The interrupter mechanism 15, comprises a suitable contact point 45, adapted to be engaged by the arm or lever 46, arranged in the circuit, and adapted to be controlled by a suitable cam 47, mounted on cam-shaft 44.

10 When brush 17 comes in contact with a contact point 18, lever or arm 46 of interrupter 15 is closed; that is to say, the cam 47 is of such construction and so timed relative to the speed of brush 17 that the lever 46 will be out

15 of contact with point 45 before brush 17 leaves a contact 18 and lever 46 will remain out of contact with point 45 until brush 17 comes into contact with the next contact point 18. The cam 47, as shown in the drawing, is 20 of elongated construction with the two opposite ends made arcuate and with two elongated flat sides. As stated, the cam-shaft 44 is driven by suitable gearing from the engine and the distributor arm 17 driven from the

25 cam-shaft 44 with the driving mechanism so timed that when the distributor arm 17 comes in contact with a contact point 18, lever 46 comes in contact with point 45 and cam 47 causes lever 46 to break contact with point 45 30 in advance of movement of distributor arm 17 out of contact with the contact point 18.

With the arrangement shown and described, 35 sparking between the brush 17 and a contact point 18 is eliminated; and as a result wear of the brush 17 is greatly reduced and burning of contacts 18 is prevented.

With cam 47, in the position shown, lever or arm 46, is held out of contact with the contact point 45 of the interrupter mechanism 40 and therefore no current is flowing to the distributor mechanism 14, which latter is also shown with the brush 17, at a point intermediate of the contact points of the distributing mechanism 14.

45 The distributing mechanism 14, of the primary circuit and the interrupter mechanism 15 are intended to be so arranged or operated that the brush 17, of the distributing mechanism is in contact with a contact point of one 50 of the primary circuits of a coil 12 of the cylinder to be fired while the lever or arm 46 of the interrupter mechanism 15 is in contact with contact point 45 of the interrupter mechanism; the cam 47 of the interrupter mechanism 15 being timed through suitable 55 gears connected to the internal combustion engine. The interruption in the primary circuit produced by cam 47, moving lever or arm 46, out of contact with point 45, induces 60 a high tension voltage in the secondary circuit which causes a synchronized spark at all spark plugs 11 in the cylinder to be fired.

65 While the distributing mechanism brush 17 is moving from one contact point to the next of the distributing mechanism 14, the

interrupter lever or arm 46 is held in the open position shown by cam 47, with the result that 70 sparking at the contact points of the distributing mechanism is prevented. In other words, no current will flow to the distributing mechanism 14 while the brush 17 thereof is moving to the next contact point; the cam 47, and the distributing mechanism being so formed and correlated that the interrupter mechanism will remain closed while the brush 75 17 is in contact with a contact point 18 of the distributing mechanism; the circuit, however, being immediately opened or interrupted as the brush 17 is about to leave a contact point of the distributing mechanism. 80

With my improved ignition system, low tension wire may be used, thus avoiding the use of high tension wire. Furthermore, with my improved system, perfect synchronization of the spark at all spark plugs in the cylinder being fired is accomplished; high tension voltage in the distributing mechanism and its conductors is eliminated and as a result high tension voltage leakage is prevented; while at the same time sparking at the contact points of the distributing mechanism and its brush are also eliminated, because when the brush enters engagement with a contact point 18, the breaker or interrupter is closed and remains so until the brush is 95 about to leave the contact point.

I have schematically illustrated my improved ignition circuit as applied to a multi-cylinder internal combustion engine employing four spark plugs to each cylinder and 100 have described the same in terms employed merely as terms of description and not as terms of limitation, as modifications are possible and may be made without, however, departing from the spirit of my invention. 105

What I claim is:

An ignition system comprising, in combination with a source of electric energy and a multi-cylinder internal combustion engine provided with four spark plugs to each cylinder, a pair of high tension coils for each cylinder with the secondaries of each coil connected to a pair of spark plugs of the same cylinder while the primaries of said pair of coils are arranged in series, distributing 110 mechanism provided with contact points arranged at predetermined distances apart and corresponding in number with the number of cylinders and a traveling brush adapted to successively engage with the contact points, an electrical connection between the primaries of said pair of coils and a contact point of the distributing mechanism and between said primaries and the source of electric energy, and interrupter mechanism electrically connected between the source of electric energy and the brush, said interrupter mechanism involving a rotatable elongated cam operatively connected with said brush, with the distance between the contact points 115 120 125 130

of the distributor mechanism and the speed of rotation of the cam so correlated that the cam will open the circuit in advance of movement of the brush out of contact with a contact point and the circuit held open until the brush comes into contact with the next succeeding contact point of the distributor mechanism.
